UNITED STATES PATENT OFFICE.

OTTO KAMMERER, OF CHARLOTTENBURG, GERMANY.

DRIVING MECHANISM FOR TRAVERSING CRANES.

SPECIFICATION forming part of Letters Patent No. 687,633, dated November 26, 1901.

Application filed May 11, 1900. Serial No. 16,390. (No model.)

To all whom it may concern:

Be it known that I, OTTO KAMMERER, a subject of the King of Prussia, German Emperor, and a resident of 148 Berliner street, Charlottenburg, near Berlin, in the Kingdom of Prussia, German Empire, have invented a new and useful Driving Mechanism for Traversing Cranes, of which the following is an exact specification.

- 10 The driving mechanism for traversing cranes of a great span width is mostly arranged in such a manner that on one side of the crane-carrier a shaft is adapted in bearings, which is driven by a motor by means of a 15 crank provided in the center of the shaft. This latter is connected with the traversing wheels of the carrier by means of cog-wheels arranged on the extremity of the shaft. It is of great importance that the rotating power 20 of the shaft be equal on both sides of the crank; but this will only be the case as long as the crane-cart will stand in the center of the carrier or bridge. If the position of the trolley be changed, the load resistance and the 25 acceleration resistance increase on the load side in proportion to the load distance from the ends—viz., $a^2:a'$ —if the distance be $a' < a^2$. Consequently the rotating resistance becomes also greater on this side. For this reason the 30 movement of the bridge will not be uniform on both sides of the same when the crane-carrier possesses a great span width in proportion to a small load.
- A better form of construction is obtained 35 in arranging the driving-motor on the trolley which drives the carrier by means of bevel-wheels adapted in bearings to be moved together with the trolley. When the trolley is moved from the center position, the greater 40 load resistance corresponds to the smaller rotating length of the shaft on the load side—viz., $a':a^2=b':b^2$ —if a' and a^2 are the distances of the motor from the driving-wheels and b' b^2 are the distances between the gearings.
- 45 This construction, often employed for cranes with great span width, has the disadvantage that the same requires a square shaft and swing-bearings, which elements get very quickly worn out. To do away with these 50 drawbacks, I employ a new arrangement
- which forms the subject-matter of my invention.
- In order to make my invention more clear, I refer to the accompanying drawing, in which similar letters denote similar parts and which 55 represents a diagram of my new construction.
- The motor is arranged on the trolley c' and drives two rope-drums n and o , which are mounted on the trolley and receive four ropes p, q, r , and s . The latter are adapted to wind up 60 or off the drums. Two wire ropes p, q run over pulleys t and u , arranged, respectively, on opposite ends of the carrier, and are anchored on one wall v of the shop, while the two other ropes r and s run over pulleys w, x , arranged, 65 respectively, on opposite extremities of the carrier and are anchored on the other side of the wall y of the shop. If the winding of the ropes is carried out in the way shown in Fig. 3, so that when the ropes p and q are wound 70 up and the ropes r and s wound off, the drums rotate in the same direction the carrier traverses the shop. If the rotation of both drums is in opposite direction, only the trolley will 75 move along the carrier, while the latter will 80 be in rest. Of course the winding of the ropes around the drums can be carried out in such a way that when the drum rotates in the same direction only the trolley will be moved, and vice versa. By means of this arrangement I obtain a uniform movement of the carrier and the trolley, for if the trolley is moved from its central position the shorter 85 rope-piece is on the side of the greater traveling resistance. The stretching of both running rope-pieces will be uniform on the right as well as on the left hand from the drums. The load on and the length of the running 90 rope-pieces are always in balance—that is, $a':a^2=b':b^2$. Thereby a' and a^2 are the distances of the load from the driving-wheels on both extremities of the carrier and b', b^2 are the length of the running rope-pieces on both 95 sides of the drums.
- Having now particularly described the nature of my said invention, what I desire to secure by Letters Patent of the United States is—
1. In an improved driving mechanism for cranes, the combination of two drums ar- 100

ranged upon the trolley, with means for rotating these drums and four ropes adapted to be wound up and off the drums and anchored to the walls of the shop, substantially as set forth.

2. In an improved driving mechanism for cranes, the combination of two drums arranged upon the trolley, with the motor arranged upon the trolley and adapted to rotate these drums in either direction, four ropes

adapted to be wound up and off the drums, said ropes being anchored to the walls of the shop, substantially as and for the purpose set forth.

In witness whereof I have hereunto set my hand in presence of two witnesses.

OTTO KAMMERER.
